US00D652580S

(12) **United States Design Patent**
Leonard

(10) **Patent No.:** **US D652,580 S**
(45) **Date of Patent:** **** Jan. 17, 2012**

(54) **PROTECTIVE ANIMAL GARMENT**

(76) Inventor: **Joseph T. Leonard**, Minneapolis, MN
(US)

(**) Term: **14 Years**

(21) Appl. No.: **29/385,539**

(22) Filed: **Feb. 15, 2011**

(51) **LOC (9) Cl.** **30-01**

(52) **U.S. Cl.** **D30/145; D30/144**

(58) **Field of Classification Search** **D30/152, D30/144, 151, 153, 154, 145, 199; 119/702, 119/712, 792-798, 758, 760, 769, 770, 784, 119/815, 818, 856, 863, 864, 905, 907, 802, 119/857, 865, 725, 771; D21/805, 804; D3/217, D3/327, 271.2; D29/101.1, 101.5, 101.3; D24/190; D34/28; 54/71**

(57) **CLAIM**

I claim the ornamental design for a protective animal garment, as shown and described.

DESCRIPTION

FIG. 1 is a perspective view of a protective animal garment; FIG. 2 is a front view of the protective animal garment of FIG. 1

FIG. 3 is a rear view of the protective animal garment of FIG. 1

FIG. 4 is a right side view of the protective animal garment of FIG. 1;

FIG. 5 is a left side view of the protective animal garment of FIG. 1;

FIG. 6 is a top view of the protective animal garment of FIG. 1;

FIG. 7 is a bottom view of the protective animal garment of FIG. 1;

FIG. 8 is a perspective view of the protective animal garment of FIG. 1 as applied on an animal; and,

FIG. 9 is another perspective view of the protective animal garment of FIG. 1 as applied on an animal showing the underneath side of the animal.

The portions shown in broken line are not claimed.
